F. J. GREGORY.

DEVICE FOR LOCATING CONCEALED CONDUCTORS.

APPLICATION FILED AUG. 26, 1915.

1,212,763.

Patented Jan. 16, 1917.

UNITED STATES PATENT OFFICE.

FRANK J. GREGORY, OF NEW YORK, N. Y.

DEVICE FOR LOCATING CONCEALED CONDUCTORS.

1,212,763.

Specification of Letters Patent. Patented Jan. 16, 1917.

Application filed August 26, 1915. Serial No. 47,419.

To all whom it may concern:

Be it known that I, FRANK J. GREGORY, a citizen of the United States, and a resident of New York city, in the county of Bronx 5 and State of New York, have invented certain new and useful Improvements in Devices for Locating Concealed Conductors, of which the following is a specification.

This invention relates to apparatus for locating or indicating the presence of a line of pipe or metallic conductor of electricity such as copper wires, that are concealed or embodied in the earth or in the walls or partitions of a building.

15 The object of the present invention is to provide means that by simply causing a special form of current to traverse the concealed pipe or conductor, and bringing a detector member in the vicinity of the pipe 20 or wire, an audible signal will be produced upon the locator being placed in a certain position relative to the pipe or wire, especially where the conductor is buried in the ground and removed a considerable distance 25 from the surface.

In the accompanying drawing illustrating one embodiment of my invention, Figure 1 shows in section, partly in elevation, the means for producing the special form of current. Fig. 2 is a side elevation of the detector with the cover removed. Fig. 3 is a cross section of the detector, indicating also the receiver; and Fig. 4 is a diagram showing the use of the apparatus.

35 The apparatus consists of an induction device for producing a high frequency current of considerable volume, that is in circuit with a generator such as a battery of not less than 6 volts; which circuit is attached to the pipe or conductor at two approximately remote points, so that the special current is caused to flow through the pipe or wire whose location is to be discovered. As shown I provide an induction coil 1, comprising a core 2 that may be the usual soft iron wires. This core or cylindrical form may have the usual insulating covering, such as a fiber tube 3. Around this is wound the primary coil 4, that is shown as comprising 45 two layers of wire such as No. 14 copper wire. A fiber tube 5 is placed on the primary for insulation, and on this is wound two layers of No. 18 copper wire forming the secondary coil 6. The primary coil has 50 one end connected by wire 7 with a battery 8. The other end 9 of the primary coil is

connected with a suitable interrupter, such as that employed with induction coils. As shown I provide a spring arm 10 located adjacent one end of the core 2, which arm is of iron or steel to be attracted by the core when magnetized; and this arm 10 I connect directly to the end 9 of the primary coil. In its normal position the arm 10 is in contact with a screw 11 carried by upright arm 12 and the contacting portions of the screw and arm 10 are preferably of platinum to withstand the sparking effect. The screw or arm 12 is connected with the other terminal of the battery 8. When the circuit is complete through the battery, the core will be magnetized by the primary coil and attract the arm 10. This will be moved away from the screw and break the circuit, that will demagnetize the core. The spring arm 10 will then move back to again make the circuit, and this arm will thus be very rapidly vibrated, as is usual with induction coils. If desired the usual condenser 13 may be employed in a shunt around the spark gap, as is customary with induction coils. By this means the secondary coil will have a current induced therein of very high frequency, but of considerable volume amperage. In this respect the form of coil I employ differs 85 from the usual spark coil, as the latter has the secondary of very much finer wire than the primary, so that a high voltage will be induced with a comparatively small amount of current.

90 The detector device that I employ comprises a locating member in the form of a coil and core, which coil is placed in a non-active closed circuit including a sounding device, such as the ordinary telephone receiver, as indicated in Fig. 3. As shown I provide a comparatively flat box or casing 14, in which is placed a core 15 of magnetic material, such as iron wires or very small iron filings. Around this core that is shown 95 of cylindrical form, I place a coil 16, preferably of copper wire of about No. 24 gage, which coil is of considerable length such as about 150 feet of the wire. The core and the coil, with their usual insulation, as 100 shown, occupy the central portion of the casing 14, and are of cylindrical form. The casing is preferably of wood or other insulating material, and is provided with terminal posts 17 and 18, connected with the 105 extremities of the coil 16 respectively. These terminals I connect with the termi-

nals of a telephone receiver 19, by wires 28 and 29 forming a closed non-active circuit. The casing 14 may also be provided with a convenient handle 20.

5 In Fig. 4 is shown one form of employing my apparatus. In this view, 21 represents a water pipe in the street, from which a pipe 22 leads into a house 23. The coil 1 is shown as having one secondary terminal 24 connected with the street main at a hydrant or plug 25. The other secondary wire 26 is shown as connected with a faucet 27 in the house. From this it will result that the current induced in the secondary will flow between the plug 25 and the faucet 27, through the pipe 21 and house pipe 22. To locate the pipe between these two points, the locating device 14 is carried by the operator with the receiver placed to the ear, and the casing 14 is brought into proximity to this pipe traversed by the current, and the casing is turned and shifted until its plane, perpendicular to the axis of the core, is caused to coincide with the pipe at its nearest location to the casing. When this is done a very distinct sound or buzzing is produced in the receiver that will indicate the location of the pipe. The casing 14 is then carried along and will serve to follow the line 30 of the pipe, because as soon as the casing is moved out of the plane of the pipe the sound will lessen or cease entirely. This means that the casing must be moved to another location and that the pipe changes its direction. The pipe can then be traced, whether 35 buried in the ground, or in the street, or whether concealed in the walls or partitions anywhere in the building.

It will be understood that a concealed 40 electric wire can be discovered in the same manner when embedded in a wall or partition, or even when buried in a conduit in the ground. It is only necessary to connect

such conductor at two remote points, and then bring the locating device so that its 45 plane will coincide with that of the conductor through which the interrupted current is caused to flow.

It will be further understood that my apparatus can be used to detect separately a 50 water pipe concealed in a wall, even though it should be in proximity to other iron objects, such as beams or structural iron work, or iron casings containing electric wires. Only the particular type of conductor 55 through which my form of high frequency current is flowing, will affect the locating device to produce the sound in the receiver, and the other iron bodies or objects, even though they are more or less magnetic, will 60 not affect the receiver.

It will be also understood that my apparatus does not depend upon any nice windings or any differential coils, and does not have to be tuned to respond to any particular current or coil. 65

Having thus described my invention, what I claim is:

Apparatus for locating concealed conductive material, comprising an induction coil 70 having both the primary and the secondary windings of a few turns of comparatively large wires, in connection with an interrupter whereby to induce a high frequency current of large amperage, and a detector 75 device consisting of a locating member having a magnetic core surrounded by a coil of considerable length of fine wire that is in closed circuit with a telephone receiver, whereby upon bringing the locator with the 80 plane of its coil parallel or coincident with the concealed conductor that is traversed by said induced current the receiver will be caused to sound.

FRANK J. GREGORY.
